UNITED STATES PATENT OFFICE.

PAUL A. DIETZ, OF FORT WORTH, TEXAS.

SILO CONSTRUCTION.

1,246,564.

Specification of Letters Patent. Patented Nov. 13, 1917.

Application filed November 7, 1916. Serial No. 129,937.

To all whom it may concern:

Be it known that I, PAUL A. DIETZ, a citizen of the United States, residing at Fort Worth, in the county of Tarrant and State 5 of Texas, have invented certain new and useful Improvements in Silo Construction, of which the following is a specification.

My invention relates to silos and more particularly to cylindrical wooden stave 10 silos; and the object is to provide single wall vertical cylindrical silos and to make silos which are strong and durable and economical. Another object is to provide means for taking up shrinkage between the staves and 15 to keep the wall air and water tight. Another object is to provide means in connection with the wall construction that will hold the wall against collapsing or caving in when subjected to strong winds. The im- 20 proved silo has the wooden construction which is a non-conductor of moisture, heat, and cold and has the improved construction by which the shrinkage can be remedied or taken up at any time. Other objects and 25 advantages will be fully explained in the following description and the invention will be more particularly pointed out in the claims.

Reference is had to the accompanying 30 drawings which form a part of this application.

Figure 1 is a side elevation of the body of a silo which shows the stave arrangement. Fig. 2 is a broken detail view of a wedge for 35 taking up shrinkage, showing the devices for operating the wedge. Fig. 3 is a plan view of a wedge, showing the clip attached to the wedge which is to be engaged by the cable for tightening the wedge. Fig. 4 is a horizontal section of a portion of the staves of the silo, showing the devices for sealing and for taking up the shrinkage. Fig. 5 is a similar view on a larger scale. Fig. 6 40 illustrates a variation in the devices for tak- 45 ing up the shrinkage.

Similar characters of reference are used to indicate the same parts throughout the several views.

One of the principal features of this im- 50 proved silo is the cylindrical single vertical wall construction. The staves consist of timbers which are two by four inches in cross-section. The timbers 1 are set vertically and as the wall is cylindrical the inner 55 edges of the timbers will be beveled suffi- ciently to make the timbers lie against each

other throughout their entire length and width. All the timbers indicated by the character 1 have grooves 2 in each side thereof and all the timbers indicated by the character 3 have grooves 2 in one side only. Bands 13 of ordinary construction hold the staves 1 in place. Sealing strips or members 4 are inserted in the grooves of adjacent timbers and extend throughout the length of 60 the timbers for the purpose of sealing the joints between the members. This construction is preferable to the tongue and groove construction because it is less expensive and the grooves can be made deeper and the sealing members will guard against shrinkage 65 leaks. The construction of the two by four inch timbers with the manner of sealing makes an inexpensive structure which is 70 relatively very strong. Of course heavier 75 timbers may be used if desirable. Provision is made for guarding against leaks by shrinkage of the timbers and also against the timbers shrinking so much that the wall would be liable to fall inwardly or down- 80 wardly. The timbers 1 and 3 are kept pressed against each other by wedges 5. The timbers 3 are placed at intervals and a wedge 5 is placed between two timbers 3. Provision is made for tightening the timbers 85 whenever the timbers shrink. Cables 6 are anchored to some rigid structure in or on the ground and connected to the wedges 5 and provided with turnbuckles 7. The wedges 5 can be forced radially outward by 90 the cables and turnbuckles by simply tightening the turnbuckles. The cables 6 thus serve as braces for the silo wall. In order to prevent angular corners about the inner 95 edges of the wedges, the angles may be filled with vertical strips 8. In order to make a horizontal pull on the wedges 5, crank brackets 9 are pivotally mounted in bearings 10 which are bolted to the timbers 3. The ends of the cranks 9 project far enough through 100 the bearings 10 to provide for expansion of the members 3. The cables 6 run on top of the crank brackets 9 which will swing downwardly to some extent when the cables are tightened. The cables 6 may be attached to 105 the wedges 5 in any suitable manner. The drawings show metal straps 11 bent to form an eye for the cables in the bight thereof and the two ends of the strap may be counter sunk in the sides of the wedge as shown in 110 Fig. 3 and the ends of the strap driven into the wedge.

Such a construction, as is described above, makes a desirable construction because it has the necessary strength and will prevent leaking caused by shrinkage and as a wooden 5 construction is a non-conductor of heat and cold, such construction is desirable because there will be very small loss of ensilage within the silo.

The wedges 5 may be forced from the outside if preferred. The same brackets 9 and cables 6 are used, but a vertical bar 12 is placed against a wedge 5. When the cable 6 pulls down on the bracket 9, the bracket 9 will force the bar 12 inwardly against the 15 wedge 5.

What I claim, is—

1. A cylindrical silo comprising timbers vertically disposed, sealing strips countersunk in adjacent faces of said timbers, bands 20 for holding said timbers in place, wedges interposed at intervals between the lateral edges of two timbers for taking up shrinkage, and adjustable cables operatively connected to said wedges for forcing the same 25 between the timbers.

2. A cylindrical silo comprising vertical staves having vertical grooves in their adjacent faces, sealing strips filling said grooves, and wedges co-extensive in length 30 with the staves interposed at intervals between the lateral edges of two staves and projecting therefrom.

3. A cylindrical silo comprising vertical staves having vertical grooves in their adjacent faces, vertical sealing strips filling 35 said grooves, vertical wedges interposed at

intervals between the lateral edges of two staves for taking up shrinkage of the staves, said wedges being co-extensive in length with said staves, and means for forcing said 40 wedges in between said staves.

4. A cylindrical silo comprising vertical staves having vertical grooves in their adjacent faces, vertical sealing strips filling said grooves, wedges co-extensive in length 45 with said staves interposed at intervals between the lateral edges of two staves, and cables acting as braces for forcing said wedges between the staves for taking up shrinkage of the staves.

5. A cylindrical silo comprising vertical staves having vertical grooves in their adjacent faces, vertical sealing strips filling said grooves, wedges co-extensive in length 50 with said staves interposed at intervals between the lateral edges of two staves, cables acting as braces for forcing the wedges between the staves, and means for causing a horizontal pull on said wedges.

6. A cylindrical silo comprising vertical 65 staves having vertical grooves in their adjacent faces, vertical sealing strips filling said grooves, wedges co-extensive in length with said staves interposed at intervals between two staves, metal straps attached to 70 and counter-sunk in said wedges and provided with bights, and cables caught in said bights for forcing said wedges between the staves.

In testimony whereof, I set my hand this 75 23rd day of August, 1915.

PAUL A. DIETZ.
